United States Patent

Des. 237,437
Patented Nov. 4, 1975

237,437

SEAT

David P. G. Williams, New York, N.Y., assignor to Futorian Corporation, Amsterdam, N.Y.

Filed May 28, 1974, Ser. No. 474,120

Term of patent 14 years

Int. Cl. D6—01

U.S. Cl. D6—63

FIG. 1.

FIG. 2.

FIG. 1 is a front perspective view of a seat showing my design in the form of a sofa; and

FIG. 2 is a front perspective view of a seat showing my design in the form of a chair.

The sides of the seats not shown are mirror images of the sides shown while the backs are plain and unornamented.

I claim:

The ornamental design for a seat, as shown and described.
